(52) **U.S. Cl.**

CLAIM

USPC **D15/5**

The ornamental design for a manifold, as shown and
described.

(58) **Field of Classification Search**

DESCRIPTION

USPC D15/1, 2, 3, 4, 5, 6

FIG. 1 is an upper perspective view of a manifold showing
our new design;

CPC F02M 35/104; F02M 35/108; F02M

FIG. 2 is a lower perspective view of the design of FIG. 1;
FIG. 3 is a front view of the design of FIG. 1;

35/1085; F02M 35/116

FIG. 4 is a rear view of the design of FIG. 1;

See application file for complete search history.

FIG. 5 is a first side view of the design of FIG. 1;

FIG. 6 is a second side view of the design of FIG. 1;

FIG. 7 is a top view of the design of FIG. 1; and,

FIG. 8 is a bottom view of the design of FIG. 1.

The broken lines shown in the drawings are included for the

purpose of illustrating the unclaimed boundary and
unclaimed portions of the manifold. The broken lines form

no part of the claimed design.
